UNITED STATES PATENT OFFICE.

JACOB FRANCIS FISHER, OF NEW YORK, N. Y.

NUT-LOCK.

SPECIFICATION forming part of Letters Patent No. 681,413, dated August 27, 1901.

Application filed June 12, 1901. Serial No. 64,238. (No model.)

To all whom it may concern:

Be it known that I, JACOB FRANCIS FISHER, a citizen of the United States, residing at New York, in the county and State of New York, 5 have invented certain new and useful Improvements in Nut-Locks, of which the following is a specification.

This invention relates to nut-locks; and it has for its object to provide an improved device of this class which will be simple and inexpensive in construction, positive in operation, and generally superior in point of durability and efficiency.

In the drawings, Figure 1 is a longitudinal 15 sectional view of a bolt and nut applied to a piece of work and embodying my improvements. Fig. 2 is a detail transverse sectional view of the same, taken upon the line *xx*, Fig. 1. Fig. 3 is a detail plan view of the 20 same, two of the working parts being shown in detached position. Fig. 4 is a similar view showing a slightly varied arrangement of parts.

Corresponding parts in all the figures are 25 denoted by the same reference characters.

Referring to the drawings, 1 designates my improved nut-lock, the several features of which are shown as embodied in a bolt 2 and a nut 3, which is applied to the bolt in the 30 customary manner.

In carrying out my invention I provide a 35 detachable locking device 4, which is carried by the nut 3 and which in operation is engaged in one of a plurality of longitudinal grooves or channels 5, formed longitudinally of the threaded surface portion 6 of the bolt. Means 7 are provided for maintaining the locking device 4 in operative position and preventing accidental displacement of the same.

40 In the preferred form of construction the locking device 4 consists of a pin 8, which is proportioned at its lower end 9^a to fit each of the grooves 5 and is provided with a headed upper end 9. The pin 8 fits in a bore 10, 45 which is formed transversely through the nut 3 from one face 11 of the same and is countersunk at its outer end, as at 12, to receive the head 9 of the pin. The face 11 of the nut is also channeled transversely, as at 13, 50 to receive a flat plate 14, which fits above the head of the pin 8 and constitutes the means for maintaining the same in operative posi-

tion. The channel 13 is preferably dovetailed in transverse dimension and tapers in width to receive the plate 14, which is similarly 55 formed, in positive locking arrangement. By countersinking the upper end of the bore 10, as above described, the head 9 of the pin 8 lies flush at its upper surface with the channeled face of the nut, and the plate 14 is thus 60 readily adjusted into and out of position in the channeled face of the nut. The channel 13 may be formed laterally in the face of the nut, so that the plate 14 may be readily forced from the same, as shown in Fig. 4. 65

The operation and advantages of my improved nut-lock will be readily understood. The nut is screwed onto the bolt into the desired position and is properly adjusted to bring the bore 10 into registration with one 70 of the grooves 5. The pin 8 is then slipped into the bore 10, and its lower end enters the groove 5 and locks the nut against rotation. The plate 14 is then fitted into the channel 13 and is wedged tightly therein, so as to prevent accidental displacement of the plate, and consequently of the pin 8. With the several 75 parts so assembled the nut and bolt are firmly locked together against relative rotation.

The metal of the plate 14 may be hard, so 80 as to enable its ready detachment from the nut, or it may be of a soft nature, so that the plate may be forced into permanent association with the nut and the nut be permanently locked to the bolt. 85

In forming the grooves 5 a sufficient number of the same are provided to enable the pin 8 to be conveniently fitted into one of the same when the nut has been adjusted into proper position. 90

The entire device is simple in construction and positive in operation, and its use is not attended by any material addition of labor or expenditure of time.

I do not desire to be understood as limiting myself to the details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right to all such varia- 95 100

tion and modification as properly falls within the scope of my invention and the terms of the following claims.

Having thus described my invention, I claim and desire to secure by Letters Patent—

1. An improved nut-lock, comprising a detachable pin carried by the nut and projecting through a bore formed at one side of the same, the bolt being formed to receive the pin in locking engagement, and detachable means for locking the pin in operative position, said means consisting of a plate which is received in a transverse channel formed in one face of the nut.

2. An improved nut-lock, comprising a pin which is carried by the nut and projects through a bore formed at one side of the same, the bore being countersunk at its upper end and said pin being provided with a head which fits in said countersunk upper end, the bolt being provided with a longitudinal groove which is formed to receive the pin in locking engagement, and detachable means for locking the pin in operative position, said means consisting of a wedge-shaped plate which is received in a transverse channel formed in one face of the nut.

3. An improved nut-lock, comprising a pin

which is carried by the nut and projects through a bore formed at one side of the same, the bore being countersunk at its upper end and said pin being provided with a head which fits in said countersunk upper end, the bolt being provided with a longitudinal groove which is formed to receive the pin in locking engagement, and detachable means for locking the pin in operative position, said means consisting of a wedge-shaped dovetailed plate which is received in a transverse similar channel formed at the same side of the nut as said bore and above the same.

4. An improved nut-lock, comprising a detachable pin carried by the nut and projecting through a bore formed at one side of the nut, and detachable means for locking the pin in operative engagement with the bolt, said means consisting of a plate which is received in a transverse channel formed in one face of the nut.

In testimony whereof I have signed my name in the presence of the subscribing witnesses.

JACOB FRANCIS FISHER.
